Primary Examiner — Ralf Seifert(74) *Attorney, Agent, or Firm* — Bushman & Associates, P.C.(57) **CLAIM**

The ornamental design for a water pump adapter, as shown and described.

DESCRIPTION

FIG. 1 is a front view of another embodiment of the water pump adapter of the present invention;

FIG. 2 is a front view of another embodiment of the water pump adapter of the present invention;

FIG. 3 is a front view of another embodiment of the water pump adapter of the present invention;

FIG. 4 is a front view of another embodiment of the water pump adapter of the present invention; and,

FIG. 5 is a front view of another embodiment of the water pump adapter of the present invention.

1 Claim, 2 Drawing SheetsFIG. 1

FIG. 2

FIG. 3

FIG. 4

FIG. 5
